C. AUGENSTEIN ET AL.

CHAIN

Filed Dec. 9. 1926

UNITED STATES PATENT OFFICE.

CARL AUGENSTEIN, OF CRANSTON, AND ROBERT VOGEL, OF PROVIDENCE, RHODE ISLAND, ASSIGNEES TO AUTOMATIC GOLD CHAIN COMPANY, A FIRM COMPOSED OF EDWIN F. M. SPEIDEL AND ALBERT R. SPEIDEL, BOTH OF EDGEWOOD, RHODE ISLAND.

CHAIN.

Application filed December 9, 1926. Serial No. 153,529.

This invention relates to an improved construction of chain or bracelet formed of a plurality of extendible links and the object of this invention is to construct such a chain or bracelet having outer guide links formed of sheet stock folded into the desired shape and an inner slide link provided with a hook-shaped portion by which it may be readily connected to and disconnected from the next adjacent link of the bracelet.

A still further object of the invention is to fold the stock of the guide link so as to provide a broad-front wall, side walls and a rear wall with a longitudinal opening 15 therein, the side walls at one end of this link being connected by a hook engaging cross bar and at the opposite end of the link the rear wall portions are provided with inwardly extending abutment portions 20 against which one end of the operating spring acts for the purpose of pressing the slide link to contracted position in its guide link.

A still further object of the invention is 25 the provision of a slide link formed into elongated band shape and having one relatively broad arm with a hook formed adjacent one end thereof, and the other or hook closing arm of the band being resilient and 30 relatively narrow and arranged to slide in the space found in the rear wall of the guide link, and to lie flush with the face thereof to complete its bearing wall and side edges of this arm being also provided with inwardly turned flanges which serve to limit 35 the extent of its hook opening motion and to also provide lateral guides for each of the operating springs.

With these and other objects in view, the 40 invention consists of certain novel features of construction, as will be more fully described, and particularly pointed out in the appended claims.

In the accompanying drawings:

Figure 1 is a perspective view showing a 45 series of links of our improved form connected together.

Figure 2 is a perspective view of the under side of one of the guide links showing the 50 abutment fingers in extended position.

Figure 3 is a bottom view of the guide link.

Figure 4 is a section of this guide link on line 4—4 of Figure 3.

Figure 5 is a perspective view of the slide 55 link showing the narrow arm of the band as provided with inwardly extending edge flanges.

Figure 6 is a bottom view of this slide link.

Figure 7 is a central sectional view of this slide link showing the resilient arm as engaging the under surface of the hook preventing it from opening outwardly.

Figure 8 is a sectional view showing a plurality of slide links in partially extended position in the guide links.

Figure 9 is a sectional edge view showing the links of the chain in the position illustrated in Figure 8.

Figure 10 is a section on line 10—10 of Figure 8.

Figure 11 shows the hook of the slide link with its tongue depressed to engage the cross bar on the next adjacent guide link.

It is found of advantage in the construction of bracelets of this character to provide a guide link of sheet stock, the blank of which is folded to provide a broad front face with narrow edge walls and having inwardly-extending rear wall portions, the edges of these walls being spaced apart to provide a longitudinally-disposed guide slot therein, and to provide an elongated band shaped slide member having a hook formed adjacent one end thereof, the front arm of the band being formed of a broad plate to slide in the guide link and close the space between the links when in extended position; also to provide the rear arm of the band somewhat narrower than the front arm and of a width to fit into the longitudinal channel or space in the rear wall of the guide link and preferably set substantially flush with the face thereof to complete the bearing wall of this guide link and also to fold the edges of this resilient arm of the hook band inwardly to limit the extent of the hook opening and also to provide lateral guiding walls for the two springs which act upon the link units and press them towards closed position; and the following is a detailed description of the present embodiment of my invention and showing one means by which these advantageous results may be accomplished.

With reference to the drawings, 10 designates the guide link, the blank of which is

formed from sheet stock and subsequently folded to provide a broad, front face 11 for the reception of suitable ornamentation, portions of which front parts are bent back providing relatively narrow side walls 12 and edges of these side walls are turned inwardly toward each other leaving a longitudinally disposed space 13 between them. The edges of these side walls at one end of the link are preferably connected together by an integral bar 14 and at the opposite end of this link its rear wall portions 15 are provided with fingers 16 which are adapted to be bent inwardly to provide abutments for the springs presently described. Another element in this link unit is a slide link member 17 which is preferably formed in elongated band shape, the front arm of which is of a width to fit and slide in the guide link between the edge walls 12 thereof as best shown in Figure 10, and one end of this broad arm or plate is turned up as at 19 into hook form, the opposite arm 20 of this band shaped link is flexible and is substantially narrower than the front arm 18 thereof, this rear arm being of a width to fill the longitudinal space 13 in the guide link and is preferably set flush with the rear wall portions 15 thereof to complete a full bearing surface for the bracelet link on the arm of the wearer.

The forward end 21 of this arm 20 is arranged to extend beneath the edge 23 of the hook to prevent it from opening outwardly and the side edges of this resilient arm are provided with inwardly extending lips or flanges 24 the same being of a depth less than the full space between the two arms 18 and 20 of the band to permit the resilient arm 20 to spring inwardly slightly just sufficient to open the hook and at the same time these flanges serve to limit the opening action of this arm so as to prevent accidental engagement of the hook from its engaged part.

In assembling the parts, this slide link is positioned in the guide link by simply sliding one within the other. The springs 25, preferably two in number, are then positioned one on either side of the inturned flanges of this arm 20. These springs are pressed and the fingers 16 are then turned inwardly to hold the springs in position between them and the rear wall 26 of the slide link, the inwardly turned flanges 24 serving to nicely guide these springs in the links to hold them in proper working alignment, and the springs serve to act upon the link elements to press them toward closed position.

After these link units have been so assembled, it is only necessary to extend the slide member of the units slightly to successively attach the hook portion 20 thereof to the cross bar 14 on the end of the next adjacent guide link thereby detachably connecting the links into a series of any desired number.

Our improved bracelet or chain is very simple and practical in construction and the unit-parts may be readily assembled, the different units detachably connected together by simply hooking one into the other and by which construction of a bracelet or chain may be made of any desired working length. 70

The foregoing description is directed solely towards the construction illustrated, but we desire it to be understood that we reserve 75 the privilege of resorting to all the mechanical changes to which the device is susceptible, the invention being defined and limited only by the terms of the appended claims.

We claim:

1. A bracelet structure comprising a series of extendible link units, each having a guide link formed of sheet stock folded to provide a broad front plate having narrow side walls with inturned portions forming parts of a rear wall with a space between the wall parts, a band-shaped slide link having a pair of oppositely disposed arms slidable in said guide link one of said arms being shaped to form a hook, the other arm being resilient 90 to close the hook, said resilient arm having inwardly turned edge flanges and being positioned flush with the rear wall parts of the guide link and slidable therebetween, spring means for moving the links of said units to contracted position, and a member on the adjacent end of the guide link to which the hook of the slide link is detachably connected.

2. A bracelet structure comprising a 100 series of extendible links, each having a guide link with a broad front wall and side walls, and a rear wall having a longitudinally disposed central opening therein, an elongated band-shaped slide link having a 105 hook at one end, the hook closing arm of the band being resilient and arranged to lie flush with and slide in the opening in the rear wall of the guide link said arm having inwardly extending side flanges, an abutment at one end of the guide link, a coil spring operatively positioned between said abutment and the fold of said slide link and guided by said side flanges, said flanges also serving to limit the extent of the hook opening motion of said resilient arm. 110

3. A bracelet structure comprising a series of extendible link units, each having a guide link formed of sheet stock folded to provide a broad front plate and relatively narrow side walls with inturned portions forming parts of a rear wall with a space between the parts, an elongated band shaped slide link having a pair of oppositely disposed arms one of a greater width than the other, 120 the broad arm having one end formed into hook shape and slidably guided between the side walls of the guide link, the narrower arm of the band being resilient and positioned to lie flush with the rear wall parts 125 130

and serving to close the hook and to slide in the space therebetween said narrower arm having inturned spring guiding side flanges forming channels between them and the 5 adjacent edge walls of the guide link, spring abutment fingers on the ends of said rear wall portions and a spring in each channel engaging said abutment fingers and the fold of said slide band link to contract the links 10 of each unit.

4. A bracelet construction comprising a series of extendible link units, each having a guide link formed of sheet stock folded to provide a broad front plate having narrow 15 side walls with inturned portions forming parts of a rear wall with a space between the wall parts, a band-shaped slide link having a pair of oppositely disposed arms slid-

able in said guide link, one of said arms being shaped to form a hook, the other being 20 resilient to close the hook, said resilient arm having inwardly turned edge flanges and set in position to slide between the rear wall parts of the guide link, abutments carried at one end of the guide link, springs inter- 25 posed and guided between the edge flanges of said slide link arm and the side walls of said guide link and engaging said abutments and the fold of the slide link, and a member on the adjacent end of the guide link to 30 which the hook of the slide link is detachably connected.

In testimony whereof we affix our signatures.

CARL AUGENSTEIN.
ROBERT VOGEL.
